STRIP FEEDING AND IMPRINTING APPARATUS

John Q. Sherman, Dayton, Ohio; Katherine M. Sherman, William C. Sherman, and Wellmore B. Turner, executors of John Q. Sherman, deceased

Application December 18, 1936, Serial No. 116,552

16 Claims. (Cl. 101—228)

This invention comprises a strip feeding and imprinting apparatus wherein successive impressions are made at uniformly spaced intervals upon a traveling strip of material simultaneously with its advancement and the imprinted strip delivered in folded condition to a storage compartment or severed into a succession of independent sheets or forms as may be desired.

For illustrative purposes, but with no intent to unduly limit the application or scope of the invention, it has been illustrated as applied to a rotary apparatus for imprinting upon checks, vouchers or the like, facsimile signatures and macerating the amount line area of the check to prevent changing the inscribed amount. It is to be understood, however, that other printing plates, cutting or punching dies or other strip treatment devices may be substituted for the printing and marking plates of the present apparatus, and that the pin type feeding means herein described may be employed for feeding strips of various materials and of different widths past operating position for other than imprinting purposes.

In the present application of the invention, a continuous succession of series connected impression receiving forms, checks, vouchers, form letters, or the like, are advanced in properly timed sequence past the imprinting member by a pin type feeding device which may be embodied in the platen element of the imprinting apparatus or may be offset relative thereto. The feeding pins progressively engage in marginally punched holes in the strip of impression receiving material.

The rotary imprinting member being intermittently engageable with the material transmits thereto successive frictional feeding impulses simultaneously with its advancement by the pin type feeding means which continues such advancement intermediate succeeding impressions. The material is thus continuously advanced at a uniform rate of speed.

The provision of marginally punched feed holes and the pin type feeding device engageable therewith enables corresponding predetermined areas of each succeeding form or check to be presented in exact registry with the imprinting devices as the succession of series connected detachable forms are fed past the imprinting position. While the marginally punched feed holes are quite desirable and necessary for positive advancement of the series connected form stationary past the imprinting position, sometimes they may be undesirable and unnecessary after the completion of the imprinting operation. Such marginal feed

holes, whenever found objectionable in checks or vouchers and similar forms, marginal strips may be removed therefrom after the feed holes have served their purpose, leaving the check or form of conventional appearance.

To this end the apparatus is provided with slitter rolls between which the strip of series connected forms is passed and by which narrow marginal areas containing the punched feed holes are removed from each side of the strip of forms leaving the checks or other forms in an unmutilated condition but still interconnected one to another. In lieu of slitting or cutting the strip to remove the punched marginal areas, the strip of forms may be scored or perforated on longitudinal lines during the initial printing operation to provide longitudinal weakened division lines. The strip may also be transversely scored or perforated to afford weakened division lines between succeeding forms. The strip may be broken on longitudinal scored or perforated lines by breaker devices instead of cutters for removing the punched margins. The imprinted strip from which the punched margins have been removed may be delivered to a receiving compartment with the imprinted forms interconnected in continuous succession.

In lieu thereof the stationery strip may be acted upon by cutters or breaking devices which transversely divide the strip into a succession of separate portions or sheets. In such case the separated checks or forms fall upon a slowly traveling apron from which they are automatically transferred in more closely assembled relation to a receiving tray removable from the machine.

The object of the invention is to provide an apparatus for imprinting or otherwise operating upon a continuous strip of material and having pin type feeding means for progressively advancing material in continuous movement past an operating position, which may be economically manufactured and which will be simple in construction, efficient in use, of compact form, having relatively few operating parts, and unlikely to get out of repair.

A further important feature of the invention is the retention of marginally punched areas upon the stationery material so long as they are useful and desirable for feeding and registry purposes, and provision of means for their automatic elimination when no longer needed and when undesirable, since they give to the forms an unconventional appearance.

A further and highly important object of the

invention is to maintain a definite travel relation of the material being advanced to the operating engagement of the imprinting or other apparatus, whereby predetermined areas of succeeding checks, forms or other portions of the strip of material may be accurately registered in the operation receiving position.

A further object of the invention is to insure uniform travel of the material in relation with the operation of the apparatus.

A further object of the invention is to incorporate in such imprinting apparatus means for automatically removing the punched marginal areas from the stationery strip and subsequently transversely dividing the strip into succeeding forms.

With the above primary and other incidental objects in view, as will more fully appear in the specification, the invention consists of the features of construction, the parts and combinations thereof, and the mode of operation, or their equivalents, as hereinafter described and set forth in the claims.

Referring to the accompanying drawings, wherein is shown the preferred but obviously not necessarily the only form of embodiment of the invention:

Fig. 1 is a perspective view of an imprinting apparatus embodying the present invention.

Fig. 2 is a reverse perspective view thereof.

Fig. 3 is a vertical sectional view of the upper portion of the apparatus illustrated in Figs. 1 and 2.

Fig. 4 illustrates a slightly modified form thereof.

Fig. 5 is a perspective view of the impression roll and combined platen and feeding roll removed from the apparatus.

Fig. 6 is a perspective view of a modified combined platen and feeding roll which is adjustable to accommodate marginally punched material of different widths.

Fig. 7 is an adjustable pin type feeding roll usable for feeding purposes only and not as a platen roll.

Fig. 8 is a further modification of the adjustable pin type feeding means.

Fig. 9 is a detail transverse sectional view of the adjustable feed pin actuating means.

Fig. 10 is a vertical sectional view of the imprinting and feeding assembly, with which is associated slitting and form detaching devices and delivery conveyors.

Fig. 11 is a front elevation thereof.

Fig. 12 is a perspective view of the stationery strip, showing the punched margins partially detached and a terminal form or section detached from the supply strip.

Fig. 13 is a perspective view of a combined feeding, trimming and cut off unit.

Fig. 14 is a cross sectional view of the unit illustrated in Fig. 13.

Fig. 15 is a detail perspective view of a portion thereof.

Fig. 16 is a detail perspective view of a portion of the strip to be fed.

Like parts are indicated by similar characters of reference throughout the several views.

The apparatus, shown for illustrative purposes in Fig. 1 includes a main frame 1 having therein supply and receiving compartments 2 and 3 from which the material operated upon is withdrawn at one side of the apparatus and returned thereto at the opposite side thereof. Mounted upon the top of the main frame 1 are uprights 4 in which

are journaled a platen roll 5 and an imprinting roll 6, cooperating with the platen roll 5, together with a series of inking and ink distributing rolls 7 by which imprinting plates carried by the roll 6 are inked preparatory to impressing the material.

At each side of the imprinting and platen rolls are guide quadrants 10, over one of which paper is drawn from the supply compartment 2 within the main frame 1, and over the other of which the material is returned to the receiving compartment 3 after having passed between the platen and imprinting rollers 5 and 6. The several rollers, including the platen and imprinting rollers and inking rollers 7, are interconnected for unison rotation by a train of intermeshing gear members 11 and are driven from a power shaft 12 by a suitable electric motor 12a mounted within the main frame 1.

The platen roll 5 may be both a platen and a feeding roll and to this end is provided with a series of radially disposed feeding pins 13 engageable in marginally punched holes 14 in the strip 15 of material to be advanced between the imprinting and platen rolls. While two groups of feeding pins, engageable in marginally punched holes in opposite margins of the strip are shown, one such group of feeding pins may be omitted and advancement of the strip effected by pins engaging holes 14 in one margin only thereof.

The feeding pins 13 may be fixedly mounted in the platen roll or carried by a separate feed roll adjacent thereto and project radially beyond the periphery of the platen or the feed roll, as the case may be, throughout the entire periphery thereof. However, these pins are preferably, though not necessarily, mounted for reciprocatory movement in radial directions whereby they are progressively projected beyond the periphery of the carrying unit or roll as they approach the path of travel of the marginally punched material with which they engage to advance the material a limited distance and are then automatically withdrawn progressively from engagement therewith to positions wholly within the periphery of the rotary carrying member, in unison with the rotation of the pin carrying unit or roll.

Such construction, per se, forms no part of the present invention but is fully set forth and claimed in United States Letters Patent to Sherman, Nos. 2,000,649; 2,000,650; and 2,000,651, dated May 7th, 1935.

The imprinting roll 6 is shown in the drawings as provided with a printing plate 19 by which a facsimile signature may be imprinted upon succeeding checks or vouchers comprising the traveling strip 15. The roll is also shown provided with an embossing plate 20 coating with a corresponding plate 21 carried by the platen roll 5 to indent or macerate the traveling checks or vouchers upon the area carrying the written amount for which the check or voucher is drawn to prevent fraudulent change of such amount.

The imprinting roll 6 is illustrated as provided with longitudinal and circumferential intersecting undercut grooves 22 in which other imprinting or embossing plates may be mounted by means of suitable clamp members 23 engaged within the undercut grooves 22.

The engagement of the imprinting roller 6 with the strip imparts thereto a frictional feeding impulse supplemental to the feeding movement transmitted by the pin feeding parts which continues uninterruptedly the advancement of the

strip intermediate printing succeeding impressions at a uniform speed.

While in Fig. 3 and also Fig. 6 the platen roll 5 is shown equipped with feeding pins 13, as an alternative construction there is shown in Fig. 4 a smooth platen roll 5 and adjacent thereto a separate strip feeding roll 24 carrying the feeding pins 13 engageable in the marginal perforations 14 of the strip as before described. This feeding roll 24 may be of any suitable type.

In order that material of different widths may be imprinted by the same apparatus the pin type feeding units are preferably mounted for axial adjustment one relative to the other. One of the pin wheel units may be incorporated in the platen roll and the other unit mounted for adjustment relative thereto as illustrated in Fig. 6. In lieu thereof the pin type feeding device 24 offset relative to the platen roll as shown in Fig. 4 may comprise an adjustable skeleton type of construction as illustrated in Fig. 7 wherein the skeleton frame and spacer discs intermediate pin wheels effectively support the material while passing in engagement with the feeding roller. The particular construction of the adjustable pin type feeding device here shown for illustrative purposes forms no part of the present invention per se, but comprises the subject matter of a copending application, Serial No. 116,553, which resulted in Patent No. 2,095,293, and to which cross reference is made. As shown in Fig. 9 the feeding pins 13 are mounted in the carrying head for reciprocatory motion in radial directions as they travel about an eccentric cam 16 the marginal flange 18 of which is engaged in notches 17 in the inner ends of the pins.

The skeleton or cage-like construction, shown in Fig. 7, comprises spaced relatively fixed heads 25 and 26, interconnected with each other at circumferentially spaced intervals by a circular series of longitudinal rods 27. This cage-like skeleton structure is mounted upon a supporting and driving shaft 28.

In the drawings the head 25 is shown provided with reciprocating disappearing feed pins 13. Mounted upon the circumferentially spaced longitudinal rods 27 and axially adjustable thereon and upon a concentric sleeve 29 surrounding the shaft 28, is a second pin wheel unit 30 also carrying a group of reciprocating disappearing feed pins 13. The feeding units 25 and 30 are relatively adjustable in an axial direction by movement of the latter toward and from the former upon the supporting rod 27 and sleeve 29 into agreement with the marginal feeding holes 14 of the material strip to be fed. Located intermediate the pin wheel units 25 and 30 are discs 31 also axially adjustable to and fro upon the rod 27 and sleeve 29 in spaced relation with each other and with the pin type feeding units 25 and 30. These discs 31 serve to support the marginally punched material being fed intermediate the points of engagement with the feeding units.

The control cams 16 within the pin type units 25 and 30 are secured to the sleeve 29 which in turn is provided with a bifurcated arm 32 by which the concentric sleeve 29 and pin control cams 16 carried thereby are held stationarily while the group of mounting rods 27 and the pin carrying heads 25 and 30 and the intermediate supporting discs 31 rotate relative thereto. To effect such rotation, the pin wheel unit 25 is provided with a hub 33 secured to the shaft 28 by a set screw 34. Thus the pin wheel units, together with the assembly of rods 27 and discs

31 rotate as a single unit, carrying therewith the pin 13 of the respective heads 25 and 30 which are caused to travel about their corresponding control cams 16 which are held stationarily by the sleeve 29 and arm 32.

In Fig. 6 there is shown a further modification wherein the features of the pin carrying platen roll 5, and those of the skeleton feed roll are combined in a single unit. In this construction, a portion of the roll comprises a platen 5a having at one end thereof the pin carrying head 25a. Projecting from the opposite end of the platen section 5a is the series of circumferentially spaced mounting rods 27 carrying at their extremities the mounting head 26. Slidingly adjustable upon the rods 27 intermediate the terminal head 26 and the platen section 5a is a pin wheel unit 30 axially adjustable toward and from the platen roll section 5a to accommodate marginally punched material of different widths. Intermediate the pin wheel unit 30 and the platen roll section 5a is a supporting disc 31 also axially adjustable as before described for supporting the portion of the strip of material beyond the end of the platen roll.

While disappearing pins, as heretofore described, are quite desirable for certain conditions of use, they are not, however, essential for operation of the present apparatus and the radial feeding pins 13 may be fixedly mounted in their respective carrying heads.

In Fig. 8 are shown two relatively spaced rotary pin wheels 36 from which project feeding pins 13. The pin wheels 36 are slidingly adjustable upon the shaft 40 whereby they may be adjusted toward and from each other to accommodate material of different widths. They are secured in their relative adjusted relation by set screws 39.

Due to slippage and lack of uniformity of feed of frictional feeding elements, whereby the forms get out of registry with the imprinting devices, the pin type feeding devices engageable in marginally punched holes of the stationery strip are not only highly desirable but are necessary to afford positive feeding action and maintain accurate registry.

When the succeeding forms have been presented to the imprinting devices in exact registry, by the coaction of the pin type feeding devices in the marginally punched holes of the strip, the marginally punched holes will have performed their only useful mechanical purpose and there no longer remains any functional reason for their retention. For aesthetic reasons, objections are sometimes raised to their unconventional appearance. Therefore, means are provided by which such marginally punched areas are automatically removed as the imprinted forms are discharged from the machine.

Referring particularly to Fig. 10, wherein is shown a further development of the apparatus illustrated in Fig. 1, there is located beyond the imprinting position a slitter roll having thereon a pair of disc cutters 41 between which the stationery strip is advanced after receiving thereon the imprinted impression. The cutting discs 41 of the slitter roll are so spaced and arranged that they engage the stationery strip inside the rows of marginally punched feed holes 14 and cut therefrom continuous marginal portions 42 as shown in Fig. 12. These punched marginal areas removed from the strip of series connected forms are waste material. The imprinted forms in their continued advancement beyond the slitter roll pass in engaging relation with a cut-off device by

which the stationery strip is transversely severed into succeeding separate forms, checks or sheets 43. The cutoff device may be of any suitable form, but for illustrative purposes has been shown in Fig. 10 as comprising a pair of coacting rolls 44-45, one of which is provided with spaced strip engaging blades 46 cooperating with pressure pads 47, upon the other roll to transversely divide the strip at predetermined spaced intervals. Since the advancement of the strip past such cutting device is under the control of the pin type feeding devices engaging in the marginally punched holes, even though such punched areas are removed before reaching the cutting rolls 44-45, the accurate registry of the division lines between succeeding forms with the cutting blades 46 is automatically maintained.

As before mentioned the stationery strip may be initially scored or perforated on both longitudinal and transverse lines upon which it is to be subsequently severed by the slitter roll discs 41 and severing devices 44-45, respectively, in which case these devices will merely break the strip on such weakened lines. However, since the progressive advancement of the strip is accurately controlled and registry automatically maintained, the strip may be severed both longitudinally and transversely by the rolls 41, 44 and 45 without preliminary scoring or weakening.

The forms or checks after being severed from the supply strip fall upon a slowly traveling apron which comprises an endless belt 46 passing about rollers or pulleys 47.

One of the apron pulleys is connected with a ratchet wheel 48 with which cooperates a pawl 49 carried by an oscillatory arm 50. The arm is actuated from any suitable moving part of the apparatus. In the present instance, it is shown connected by a link 51 with a disc 52 connected to and rotating with one of the cut-off rolls 45. The link, arm and pawl combination transmits to the traveling apron 46 an intermittent advance movement, by which the severed imprinted forms deposited thereon are slowly advanced.

As the deposited forms reach the end of the traveling apron they fall therefrom onto a tray 53 removably supported upon a traveling conveyor 54. This conveyor is actuated from the traveling apron, but at a lesser rate of speed by a chain drive 54' operating over a pair of sprockets 55, one of which is connected for unison rotation with the ratchet wheel 48 and apron pulley 47, and the other of which is operatively connected with a corresponding sprocket which drives the chain 55 having engagement with a larger sprocket 57 connected to and driving the conveyor 54.

Due to the differential speed of the apron 48 and conveyor 54, the forms are more closely deposited on the tray 53 than on the apron 46 and are stacked in closely overlapping relation on such conveyor tray.

The apparatus being designed for high speed operation, the traveling apron and conveyor arrangement facilitates delivery of the severed forms.

In Figs. 13 to 15 there is shown a more compact arrangement of the feeding, trimming and cutting devices, wherein the roller 45, in addition to its coaction with the roller 44 in breaking or cutting the strip transversely, carries the feeding pins 13 engageable in the marginally punched holes of the strip and also provides an abutment for the trimming discs 41' which sever the punched margins of the strip as it is fed between the rolls.

The rollers 44 and 45 are interconnected for unison rotation by intermeshing gears 57. The upper roller 44 carries a blade 58 which coacts with an insert 59 of rubber, fiber or similar material in the lower roller 45. The blade 58 may be either a sharp cutter blade, or it may be a blunt blade adapted to break the strip on a previously scored or weakened division line. The blade 58 and insert strip 59 do not extend the full length of the rolls nor the width of the strips, but terminate either coincident with or slightly inwardly of the path of the trimmer discs 41' upon the roll. If the blade extends to or slightly beyond the path of travel of the trimmer discs upon the roll the transverse cut or break imposed by the blade 58 will be subsequently intersected by the longitudinal cuts effected by the trimmer discs 41' resulting in complete separation of the forms, checks or sheets as is shown in Fig. 12. It is preferred however, that the blade 58 and insert strip 59 shall terminate in slightly inwardly spaced relation with the path of travel of the trimmer discs 41' whereby a short unbroken or uncut portion will remain after the punched margins have been removed, thus leaving the trimmed checks or forms interconnected in series but capable of being easily separated manually as may be required.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and that the invention is, therefore, claimed in any of its forms or modifications within the legitimate and valid scope of the appended claims.

I claim:

1. In an imprinting apparatus wherein a continuous strip of record material receives a succession of impressions at spaced intervals, a rotary printing element having printing engagement with the strip of record material throughout a portion only of its revolution, and a pin type feeding device having progressive engagement in a succession of longitudinally spaced holes in the record strip, actuating means for the rotary printing element and the pin type feeding device whereby the strip is advanced by the pin type device at a lineal speed coincident with the peripheral speed of the printing element, means for dividing said strip into sections along its length including a pair of coacting rolls, strip engaging blades on one of the rolls and cooperating pressure pads upon the other of the rolls, and means for removing portions of the strip along the lateral margins thereof, the pin type feeding device being so constructed and arranged as to feed the strips in timed relation with the several devices to present prescribed longitudinally spaced areas thereof in registry with the imprinting operation of the rotary imprinting element and to prevent other longitudinally spaced

areas thereof in accurate registry with the strip dividing means coincident with the operation thereof and advancing the strip past the means for removing portions of the strip along the lateral margins thereof.

- 5 2. An imprinting apparatus wherein a continuous strip of marginally punched material receives thereon a succession of impressions at spaced intervals, including a rotary printing element having imprinting engagement with the strip throughout a portion only of its revolution to which it frictionally imparts an advance feeding influence, and a pin type feeding means engageable progressively in longitudinally spaced holes in the strip to continuously advance the strip both during and intermediate periods of engagement of the imprinting member, actuating means for the imprinting member and pin type feeding means whereby the said imprinting member and pin type feeding means advance the strip at the same rate of speed, means for dividing said strip into sections along its length including a pair of coating rolls, strip engaging blades on one of the rolls and cooperating pressure pads upon the other of the rolls, and means cooperating with one of the rolls for removing portions of the strip along the lateral margins thereof, the pin type feeding device being so constructed and arranged as to feed the strip in timed relation with the several devices to present prescribed longitudinally spaced areas thereof in registry with the imprinting position coincident with the imprinting operation of the rotary imprinting element and to present other longitudinally spaced areas thereof in accurate registry with the strip dividing means coincident with the operation thereof and advancing the strip past the means for removing portions of the strip along the lateral margins thereof.
- 40 3. An imprinting apparatus wherein a continuous strip of material having longitudinally spaced holes therein receives thereon a succession of impressions at spaced intervals, including a rotary printing element having imprinting engagement with the strip throughout a portion only of its revolution to which it frictionally imparts an advance feeding influence, means for continuously advancing the strip at a uniform rate of speed including a pin type feeding means engageable in the longitudinally spaced holes of the strip and actuating means by which the rotation of the imprinting member and the action of the pin type feeding means are synchronized, the pin type feeding means including axially spaced pin wheel units and mounting means for at least one of the pin wheel units including a plurality of parallel spaced rods upon which the pin wheel unit is slidably adjustable laterally into different strip feeding positions, means for dividing said strip into sections along its length including a pair of coating rolls, strip engaging blades on one of the rolls and cooperating pressure pads upon the other of the rolls, and means for removing portions of the strip along the lateral margins thereof, the pin type feeding device being so constructed and arranged as to feed the strip in timed relation with the several devices to present prescribed longitudinally spaced areas thereof in registry with the imprinting position coincident with the imprinting operation of the rotary imprinting element and to present other longitudinally spaced areas thereof in accurate registry with the strip dividing means coincident with the operation thereof and advancing

the strip past the means for removing portions of the strip along the lateral margins thereof.

4. An imprinting apparatus wherein a continuous strip of material having longitudinally spaced holes therein receives thereon a succession of impressions at spaced intervals, including a rotary printing element having imprinting engagement with the strip throughout a portion only of its revolution to which it frictionally imparts an advance feeding influence, 10 a pin type feeding device having operative engagement in longitudinally spaced holes in the strip simultaneously with the engagement thereof by the imprinting member and continuing its operative engagement therewith subsequent to the disengagement of the imprinting member to continuously advance the strip at a uniform rate of speed, the pin type feeding means including axially spaced pin wheel units and mounting means for at least one of the pin wheel units including a plurality of parallel spaced rods upon which the pin wheel unit is slidably adjustable laterally into different strip feeding positions, means for dividing said strip into sections along its length including a pair of coating 20 rolls, strip engaging blades on one of the rolls and cooperating pressure pads upon the other of the rolls, and means for removing portions of the strip along the lateral margins thereof, the pin type feeding device being so constructed and arranged as to feed the strip in timed relation with the several devices to present prescribed longitudinally spaced areas thereof in registry with the imprinting position coincident with the imprinting operation of the 30 rotary imprinting element and to present other longitudinally spaced areas thereof in accurate registry with the strip dividing means coincident with the operation thereof and advancing the strip past the means for removing portions of the strip along the lateral margins thereof.
5. An imprinting apparatus wherein a continuous strip of record material having therein a succession of longitudinally spaced holes receives thereon a succession of relatively spaced impressions including a rotary imprinting member, a pin type feeding device engageable in the spaced holes in the strip, conjointly advancing the strip past impression receiving position by simultaneous frictional and positive feeding engagement therewith during a part of the cycle of operation, said pin type feeding device acting to further advance the strip at a uniform rate of speed subsequent to the disengagement of the imprinting member, the pin type feeding means including axially spaced pin wheel units and mounting means for at least one of the pin wheel units including a plurality of parallel spaced rods upon which the pin wheel unit is slidably adjustable laterally into different strip feeding positions, means for dividing said strip into sections along its length including a pair of coating rolls, strip engaging blades on one of the rolls and cooperating pressure pads upon the other of the rolls, and means for removing portions of the strip along the lateral margins thereof, the pin type feeding device being so constructed and arranged as to feed the strip in timed relation with the several devices to present prescribed longitudinally spaced areas thereof in registry with the imprinting position coincident with the imprinting operation of the rotary imprinting element and to present other longitudinally spaced areas thereof in accurate registry with the strip dividing means coincident 70

with the operation thereof and advancing the strip past the means for removing portions of the strip along the lateral margins thereof.

6. In an apparatus wherein a rotary imprinting roller is actuated to imprint a signature or other indicia upon successive series connected detachable checks or the like, a main frame having therein strip supply and receiving compartments for a continuous strip of series connected checks to be imprinted, an imprinting roller and a platen between which the strip of checks is progressively advanced from the supply to the receiving compartment, a pin type feeding means engageable in longitudinally spaced holes in the strip of checks for advancing the strip of checks from the supply compartment past the platen and imprinting roller and thence to the receiving compartment, actuating means for the pin type feeding means and imprinting roller in timed sequence to present predetermined areas of succeeding checks of the series in position to be impressed by the imprinting roller, and means operating upon the strip in sequence with the imprinting roller for lessening the width of the strip, the pin type feeding means being so constructed and arranged as to advance the strip past the means for lessening the width of the strip.

7. In an apparatus of the character described, means for progressively feeding a continuous strip of series connected stationery past an operation receiving position, including a main frame, strip supply and receiving portions therein, relatively spaced guide portions over which the strip is withdrawn from the supply portion and advanced to the receiving portion, strip treating means mounted in the main frame and engaging the strip during its progress from one guide portion to the other, a pin type roller the pins of which progressively engage in longitudinally spaced holes in the strip intermediate the guide portions to advance the strip relative to the strip treating means, actuating means for operating the pin type feeding roller and the strip treating means in timed sequence, and means operating upon the strip in sequence with the treating means for lessening the width of the strip and transversely dividing the strip into sections throughout its length, the pin type roller being so constructed and arranged as to feed the strip in timed relation with the several devices to present prescribed longitudinally spaced areas thereof in registry with the strip feeding means coincident with the treating operation of the strip feeding means and to present other longitudinally spaced areas thereof in accurate registry with the strip dividing means coincident with the operation thereof and advancing the strip past the means for lessening the width of the strip.

8. In an apparatus of the character described, a main frame having strip supply and receiving areas therein, relatively spaced guides about one of which a strip of material may be advanced from the supply area and about the other of which such strip is delivered to the receiving area of the main frame, a rotary platen roll and a pin type feeding device mounted intermediate the guides and engageable in successions of longitudinally spaced holes in the strip for advancing it past the platen roll from the supply to the receiving areas of the main frame, a superstructure on said main frame, an imprinting roller therein cooperating with the platen roll to impress the strip during its advance movement, ink

distributing rollers in said superstructure for applying ink to the imprinting roller, means for actuating the pin type feeding devices and imprinting roller in timed relation, and means operating upon the strip in sequence with the imprinting roller for lessening the width of the strip and transversely dividing the strip into sections throughout its length, the pin type feeding device being so constructed and arranged as to feed the strip in timed relation with the several devices to present prescribed longitudinally spaced areas thereof in registry with the imprinting position coincident with the imprinting operation of the imprinting roller and to present other longitudinally spaced areas thereof in accurate registry with the strip dividing means coincident with the operation thereof and advancing the strip past the means for removing portions of the strip along the lateral margins thereof.

9. In an apparatus of the character described, the combination of an imprinting member, a pin type feeding means engageable in spaced holes in a continuous strip of record material for advancing the strip past and in cooperation with the imprinting member, means for dividing said strip into sections along its length, and a strip section conveying means for stacking the strip sections in closely overlapping relation and delivering the strip sections to a point of discharge, and means for actuating the pin type feeding means, the imprinting member and strip dividing means in synchronism, the pin type feeding means being so constructed and arranged as to feed the strip in timed relation with the several devices to present prescribed longitudinally spaced areas thereof in registry with the imprinting position coincident with operation of the imprinting member and to present other longitudinally spaced areas thereof in accurate registry with the strip dividing means coincident with the operation thereof and to the conveying means and stacking means in timed sequence.

10. In an apparatus of the character described, the combination of a rotary imprinting member, a pin type feeding device including spaced pin wheel units for positively advancing a strip of record material continuously in cooperation with intermittent frictional advancement thereof by the imprinting member, a means coacting with the pin wheel units for removing portions of the continuous strip along the lateral margins thereof, means for transversely dividing said strip into sections throughout its length for delivery to a point of discharge.

11. In an apparatus of the character described, an imprinting member adapted to impress indicia in successive spaced positions on a continuous strip of record material having therein a succession of longitudinally spaced holes, a pin type feeding device including spaced pin wheel units associated with the imprinting member and engageable in the longitudinally spaced holes in the strip for advancing the strip past the imprinting member in timed relation therewith, and means coacting with the pin wheel units and engaging the strip for removing from the strip the portions having the holes therein.

12. In an apparatus of the character described, an imprinting member adapted to impress indicia on a continuous strip of record material, a pin type feeding device for advancing the continuous strip past an imprinting position, and means operating upon the strip in sequence with the imprinting member for lessening the width of said strip and transversely dividing said strip into sec-

tions throughout its length, and traveling conveying means for stacking the sections in overlapping relation and delivering said sections to a point of discharge from the apparatus, the pin type feeding means being so constructed and arranged as to feed the strip in timed relation with the several devices to present prescribed longitudinally spaced areas thereof in registry with the imprinting position coincident with operation of the imprinting member and to present other longitudinally spaced areas thereof in accurate registry with the strip dividing means coincident with the operation thereof and to the conveying means and stacking means in timed sequence.

13. In an apparatus of the character described, an imprinting member adapted to impress indicia on a continuous strip of record material, a pin type feeding device for advancing the continuous strip past the imprinting member, and means coacting with the strip in sequence with the imprinting member for lessening the width of said strip, and transversely dividing said strip into sections throughout its length, and conveying means moving in synchronism with the operation of said strip dividing means for stacking the sections in overlapping relation and delivering detached stacked sections to a point of discharge from the apparatus, the pin type feeding means being so constructed and arranged as to feed the strip in timed relation with the several devices to present prescribed longitudinally spaced areas thereof in registry with the imprinting position coincident with operation of the imprinting member and to present other longitudinally spaced areas thereof in accurate registry with the strip dividing means coincident with the operation thereof and to the conveying means and stacking means in timed sequence.

14. In an apparatus of the character described, an imprinting member adapted to impress indicia on a continuous strip of record material, a pin type feeding device for advancing the continuous strip past the imprinting member, and means operating upon the strip in sequence with the imprinting member for lessening the width of said strip and dividing said strip transversely into sections throughout its length, and intermittently operating conveying means moving in synchronism with the operation of said strip dividing means for stacking the sections and delivering said stacked sections to a point of discharge from the apparatus, the pin type feeding means being

so constructed and arranged as to feed the strip in timed relation with the several devices to present prescribed longitudinally spaced areas thereof in registry with the imprinting position coincident with operation of the imprinting member and to present other longitudinally spaced areas thereof in accurate registry with the strip dividing means coincident with the operation thereof and to the conveying means and stacking means in timed sequence.

15. In an apparatus of the character described, an imprinting member adapted to impress indicia on a continuous strip of record material, a pin type feeding device for advancing the continuous strip past the imprinting member, and means operating upon the strip in sequence with the imprinting member for lessening the width of said strip and dividing said strip transversely into sections throughout its length, and conveying means moving in synchronism with the operation of said strip dividing means for stacking the sections and delivering said stacked sections to a point of discharge from the apparatus, the pin type feeding means being so constructed and arranged as to feed the strip in timed relation with the several devices to present prescribed longitudinally spaced areas thereof in registry with the imprinting position coincident with operation of the imprinting member and to present other longitudinally spaced areas thereof in accurate registry with the strip dividing means coincident with the operation thereof and to the conveying means and stacking means in timed sequence.

16. In a motor actuated strip imprinting apparatus, an imprinting device intermittently engageable with a traveling strip of impression receiving material having therein a longitudinal succession of spaced holes, feeding means therefor including spaced pin wheel units having continuous feeding engagement in successive holes in the strip, means for advancing the strip simultaneously with the engagement of the imprinting member therewith and for continuing such advancement intermediate successive engagements thereof, and a cutting device coacting with the pin wheel units for removing from the material successive portions containing said spaced holes, and a motor for actuating the imprinting, feeding and cutting devices in synchronism.

JOHN Q. SHERMAN.

CERTIFICATE OF CORRECTION.

Patent No. 2,172,414.

September 12, 1939.

JOHN Q. SHERMAN.

It is hereby certified that error appears in the printed specification of the above numbered patent requiring correction as follows: Page 4, first column, line 57, for the reference numeral "48" read 46; and second column, line 75, for the word "prevent" read present; and that the said Letters Patent should be read with this correction therein that the same may conform to the record of the case in the Patent Office.

Signed and sealed this 31st day of October, A. D. 1939.

(Seal)

Henry Van Arsdale,
Acting Commissioner of Patents.
